(57) **CLAIM**

The ornamental design for a counter holder for a precision press machine, as shown and described.

DESCRIPTION

FIG. 1 is a left top perspective view of a counter holder for a precision press machine according to the present design; FIG. 2 is a top view thereof;

FIG. 3 is a bottom view thereof;

FIG. 4 is a left side view thereof;

FIG. 5 is a right side view thereof;

FIG. 6 is a rear view thereof;

FIG. 7 is a front view thereof;

FIG. 8 is a right top perspective view thereof; and,

FIG. 9 is a bottom perspective view thereof.

The broken lines in the drawings depict unclaimed environmental subject matter.

1 Claim, 9 Drawing Sheets
